NICKOLAS G. LAGIOS, OF MINNEAPOLIS, MINNESOTA

DESIGN FOR A BUILDING OF DIRIGIBLE AIRCRAFT DESIGN

Application filed October 19, 1931. Serial No. 41,434. Term of patent 14 years.

To all whom it may concern:

Be it known that I, NICKOLAS G. LAGIOS, a citizen of the United States, residing at Minneapolis, in the county of Hennepin and State of Minnesota, have invented a new, original, and ornamental Design for Building of Dirigible Aircraft Design, of which the following is a specification, reference being had to the accompanying drawings, forming part thereof.

Fig. 1 is a view in side elevation of said building;

Fig. 2 is a vertical section on line 2—2 of Fig. 1, as indicated by the arrows; and

Fig. 3 is a section taken on line 2—2 of Fig. 1, looking in the direction opposite to the arrows.

I claim:

The ornamental design for a building of dirigible aircraft design, as shown.

NICKOLAS G. LAGIOS.
